(57) **CLAIM**

The ornamental design for display screen or portion thereof with graphical user interface as shown and described.

DESCRIPTION

FIG. 1 is a front view of a display screen or portion thereof with graphical user interface showing the claimed design; and,

FIG. 2 is a second embodiment thereof.

The outermost broken lines in FIG. 1 and FIG. 2 show a display screen or portion thereof, and form no part of the claimed design. The other broken lines in FIG. 1 and FIG. 2 show portions of the graphical user interface that form no part of the claimed design.

1 Claim, 2 Drawing Sheets
